MACHINE FOR WRAPPING AND BOXING
ARTICLES

John Van Buren, Brooklyn, N. Y.

Application March 27, 1933, Serial No. 663,076

25 Claims. (Cl. 93—3)

This invention relates to a machine for wrapping and boxing articles, such as cakes of soap.

At the present time it is customary to enclose cakes of soap in wrappers and in some cases the 5 wrapped cakes are assembled in boxes. When this is done the cakes are wrapped in the wrapping machine and are then boxed in a separate machine.

This invention has for its object to provide a 10 machine so constructed and arranged that the articles will be wrapped and the wrapped articles will be boxed in a single machine.

Another object of the invention is to provide a 15 machine so constructed and arranged as to feed and wrap the articles, fold blanks into boxes, enclose the wrapped articles in the boxes and close the boxes.

Further objects of the invention will appear 20 from the following specification taken in connection with the drawings which form a part of this application, and in which

Fig. 1 is a top plan view of the machine constructed in accordance with the invention;

Fig. 2 is an end elevation of the machine shown 25 in Fig. 1 looking to the right in said figure;

Fig. 3 is an elevational view showing the box making portion of the machine;

Fig. 4 is a top plan view of the structure shown 30 in Fig. 3;

Fig. 5 is a sectional elevation looking to the front of the mechanism for feeding the blanks which are used to form the cartons or boxes, this view being taken substantially on line 5—5 of Fig. 6;

Fig. 6 is a sectional elevation taken at right angles to Fig. 5 showing the feed for the carton 35 or box blanks;

Fig. 7 is a sectional elevation taken substantially on line 7—7 of Fig. 6 and showing one set 40 of blank feeding rolls;

Figs. 8, 9, and 10 are transverse sectional elevations similar to Fig. 7, taken substantially on lines 8—8, 9—9, and 10—10 of Fig. 3 and showing the successive folding mechanisms for the carton blank;

Fig. 11 is a horizontal sectional view or sectional plan view showing a part of the mechanism for feeding the folded blanks;

Fig. 12 is a sectional elevation taken at right angles to Fig. 11 and substantially on line 12—12 45 of Fig. 11;

Fig. 13 is an elevational view partly in section, showing the presser means for closing the box or carton, this view being taken substantially on line 13—13 of Fig. 4;

Fig. 14 is a view similar to Fig. 13 but showing the clamping or presser members open instead of closed;

Fig. 15 is a sectional elevation taken substantially on line 15—15 of Fig. 13; 5

Fig. 16 is a plan view of the blank before it is folded;

Fig. 17 is a prospective view showing the blank 10 folded into a rectangular tube, the ends being open;

Figs. 18 to 22 inclusive, are elevational views showing the mechanism for feeding the open ended carton through its successive positions of movement, these views being somewhat diagrammatic; 15

Fig. 23 is an elevational view partly in section, showing the article feed conveyor, wrapper, feed mechanism and tumbler blocks for enclosing the article in the wrapper;

Fig. 24 is a plan view of the construction shown 20 in Fig. 23;

Fig. 25 is a view similar to Fig. 23 but showing the parts in section, this view illustrating the article feeding, wrapper feed and mechanism for enclosing the article in the wrapper; 25

Fig. 26 is a detail sectional elevation similar to Fig. 25 but showing an article being fed into the receiving pocket in which it is partially wrapped and another article being ejected from the other folding pocket; 30

Fig. 27 is a sectional elevation taken at right angles to Fig. 25 and substantially on line 27—27 of Fig. 25, this view illustrating the article feed, carton feed and a part of the wrapper folding means; 35

Fig. 28 is an elevational view showing the operating mechanism for the folding pockets;

Fig. 29 is an elevational view taken at right angles to Fig. 28;

Fig. 30 is a sectional elevation showing the pockets positioned with their open ends toward each other, in which position the article in the lower pocket is transferred to the upper pocket; 40

Fig. 31 is an elevational view taken at right angles to Fig. 30;

Fig. 32 is a plan view of a portion of the wrapper folding mechanism, this view being taken on line 32—32 of Fig. 31; 45

Fig. 33 is a top plan view of the mechanism for closing the cartons after the article has been placed therein;

Fig. 34 is an elevational view partly in section, taken at right angles to Fig. 33;

Fig. 35 is a sectional elevation taken substantially on line 35—35 of Fig. 34; and 50 55

Figs. 36, 37, 38, and 39 are sectional elevations on an enlarged scale taken substantially on lines 36—36, 37—37, 38—38, and 39—39 of Fig. 34, these views illustrating the mechanism for closing the ends of the carton.

The invention briefly described consists of a machine comprising a plurality of successively acting mechanisms for enclosing an article such as a cake of soap in a wrapper, placing the wrapper in a box and closing the box or carton. These mechanisms include means for feeding the wrappers and for folding the wrappers around the articles, means for feeding box or carton blanks and for folding the blanks into open ended tubes and thereafter feeding the tubes or open ended cartons over the articles, and means for closing the open ends of the cartons after the wrapped articles have been placed therein. In the particular embodiment of the invention illustrated the articles are fed by an endless chain, the wrappers are fed intermittently, the articles are discharged from the feeding chain and the wrappers and articles are successively placed in folding pockets and discharged from the pockets. The carton blanks are fed to folding mechanism which folds them into open ended tubes or cartons and then feeds the open ended cartons over the wrapped articles and subsequently closes the ends of the cartons. Further details of the invention will appear from the following description.

As above stated, the machine embodying the invention comprises a plurality of mechanisms which will be described under a plurality of headings.

Wrapper feeding mechanism

This structure is illustrated particularly in Figs. 23, 24, and 25. The sheets or wrappers are positioned in a hopper H having an open bottom, as shown in Fig. 25. The wrappers are fed successively from the hopper by means of a friction engaging member such as an arcuate lug 50 of rubber or like material carried by a rotatable roll 51 which in turn is mounted on a shaft 52. The bottom sheet or wrapper is engaged by an upwardly projecting pin 53. As the roll 51 rotates in the direction of the arrow shown in Fig. 25 the sheets will be successively fed from the hopper to feed rolls 54 and 55. A shaft 70, driven by sprocket and chain connections 71, (see Figs. 24 and 25) drives the shaft 52' by a sprocket and chain connection 56, 51, and 58. The shaft 52' is connected to drive the shaft 52 and feed rolls 51 and 55 by means of gears 59 and 60 and the gear 60 is connected to drive the roll 54 by a gear 61.

Article feeding mechanism

The cakes of soap or, if desired, other articles are fed in the machine by an endless chain 65 which comprises a plurality of elliptical pockets 66 which are pivotally connected at their ends to chains 67, 68. The top or upper lap of the chain travels along a table or platform 69 on which the cakes are supported. The chain is intermittently actuated by means of ratchet and pawl mechanism shown particularly in Figs. 23, 25, and 27. A cam shaft 10 is connected by a sprocket and chain drive 71 to the shaft D and is provided with a cam 72 which engages a roller 73 on a connecting rod or pitman 74, the other end of the pitman having pivoted thereon a pawl 75 which engages and rotates a ratchet 76 loosely mounted on a shaft 77. The ratchet 76

has a hub 80 on which is mounted a gear 81 which meshes with a gear 82 secured to a shaft 83 on which are also mounted sprocket wheels 84 and 85 which drive the chains 67 and 68. As the ratchet wheel 76 is rotated step by step the pockets 66 will be fed step by step.

The cakes are discharged from the chain pockets by means of a vertically movable plunger 90 having a head 91 at the upper end thereof for engaging the cakes. The plunger, as shown particularly in the plan view Fig. 24 is angular and extends inwardly between the upper and lower laps of the chain. The plunger is connected to a vertically movable slide 92 which in turn is connected to one arm 93 of a bell crank lever 15 which is pivoted at 94, the other arm 95 of the lever being connected to a pitman 96 having a roller 97 positioned in a cam 98 mounted on the other end of the shaft 70 from the cam 72. As the shaft 70 rotates the pitman 96 will be reciprocated and will actuate the bell crank lever 95, 93 about the pivot 94 and raise and lower the slide 92 and plunger 90.

Wrapper folding mechanism

This mechanism is particularly shown in Figs. 23, 24, 25, and 27 to 32 inclusive. When the wrapper has been fed by the rollers 54 and 55 the cake will be raised on the plunger head 91 and will be positioned between oppositely acting plungers 100 and 101. The plunger 100 is carried by a slide 102 having a rack 103 engaged by a gear 104 which is oscillated by a quadrant gear 105 pivoted on a shaft 106. An arm 107 is connected to the hub of the quadrant gear and is also pivoted to a pitman 108 having a roller 109 riding in a cam 110 which is carried by a shaft 111. Shaft 111 has a gear 112 which meshes with a gear 59 on shaft 52 and is driven thereby.

A pair of oscillatable pockets P' and P² are mounted for oscillation on a pair of shafts 115 and 116. The pocket P' is provided with side walls or plates 117 and 118, the walls 117 being spring pressed toward the walls 118. The pockets are open at their outer ends and the inner ends of the pocket are formed by plates 120 which are connected to the ends of the plungers 101. The heads are movable between the side walls of the pockets and the plungers are slidably mounted and are frictionally held in inner or outer position as the case may be.

In Fig. 26 a cake and wrapper are being fed into the pocket P' by the plunger 100, one edge of the cake being engaged by the plunger 100 and the other edge being engaged by the head 120 on the plunger rod 101. It will be seen from the showing in Fig. 6 that the wrapper will be placed around two sides of the cake as the cake and wrapper are being fed into the pocket P'.

After the cake and wrapper have been fed into the pocket P' the pockets P' and P² are rotated through 90°, the pocket P' in an anticlockwise direction and the pocket P² in a clockwise direction. After this rotation the pockets will be positioned as shown in Figs. 30 and 31. When they have reached this position the plungers 101 of the pockets P' will be actuated by means of a bar or plate 125 carried by a lever 126 which is mounted on a pivot 127 and is actuated by an eccentric pin 128 carried by a shaft 129. The shaft 129 has a gear 130 which meshes with a gear 131 mounted on a shaft 132 which also has secured thereto a gear 133 driven by a gear 134 carried by the drive shaft D. As the lever 126 is swung in an anticlockwise direction the plunger 75

101 of the pocket P' will move the cake disposed therein, as shown in Fig. 30, from the pocket P' into the pocket P². The upper edge of the cake will engage the plunger head 120 and the head 5 will move into the pocket P² with the cake.

The pocket P² is provided with pivoted crimping or folding members 135 and 136 which are carried by spindles 137 and 138, arms 139 and 140 extending in the opposite direction from the pivots or spindles 137 and 138 from the crimping or folding members 135 and 136. The folding members are actuated by springs 140 into the position shown in Fig. 29 and crimp the wrapper about the ends of the cake. When the pocket P² is swung or oscillated through 90° from the position shown in Figs. 25 and 28 to the position shown in Figs. 30 and 31, the arms 139 and 140 will engage an abutment or bar 141 which will cause the crimpers 135 and 136 to swing outwardly away from each other and away from the crimping position shown in Fig. 29. The crimpers will be held in this position as the cake and wrapper is being fed from the lower pocket P' to the upper pocket P². After this has been accomplished the pockets will be oscillated again to the position shown in Figs. 25 and 28 whereupon the crimpers will engage the ends of the wrapper. The wrapper will also be pressed against the cake in the pocket P² by resilient presser members 142 and 143 shown in Fig. 29. This is also accomplished by a spring pressed side wall or block 144 which presses the cake and wrapper against the other wall 145. The position of the spring actuated or spring pressed wall 35 147 in the pocket P' is determined by springs 150 which hold the wall against adjustable stops 151.

After the cake has been placed in the upper pocket P² it is ejected by the plungers 101 which are actuated by a plate 152 carried by an arm 40 153 which is mounted on a pivot 154 and is actuated by an eccentric pin 155 which is carried by the gear 133.

The pockets P' and P² are oscillated by rack and pinion operating means shown particularly in Figs. 27 and 28. The shafts 115 and 116 have secured thereto quadrant gears 160 and 161 which are engaged respectively by racks 162 and 163, the racks being secured to a slide 164 which carries a roller or pin 165 actuated by a cam 166. The cam 166 is mounted on a shaft 167 which also carries a sprocket wheel 168 which is driven by a chain 169 which in turn is driven by a sprocket 170 mounted on a drive shaft D. Thus, as the cam 166 is rotated the slide 164 will be reciprocated causing the pockets to be oscillated in the manner described to receive, transfer and discharge the article and wrapper.

Carton blank feed and folding mechanism

60 This mechanism is illustrated particularly in Figs. 3 to 10 inclusive, and 12 to 22 inclusive. The blanks for forming the cartons or boxes are contained in a hopper J shown in Fig. 6 and are fed from the bottom of the hopper by a lug or feed member 175 carried by a roll 176 which is mounted on a shaft 177. The shaft 177 is driven from a shaft 178 by a bevel gear connection 179, 180. The shaft 178 is driven by a sprocket and chain connection 181 to the shaft D.

70 The shaft 177 has mounted thereon a gear 182 which meshes with a gear 183 which in turn drives a gear 184 of a feed roller 185. Gear 184 meshes with a gear 186 which drives the coacting feed roller 187.

75 The blanks are positioned in the hopper J in

the position shown in Fig. 16. As they are fed from the hopper one end D of the blank B passes over a glue roller 191 carried by a shaft 192 which is positioned above a glue receptacle 193. As the roller 191 rotates the glue will be carried 5 around from the receptacle and will be positioned on the flap C of the blank B. The shaft 192 is driven by a gear connection 194, 195 from the roller 185.

From the feed rollers 185, 187 the blank passes 10 downwardly through a guideway or chute 196 to a supporting surface 198 of a rectangular support 199. A pair of supporting rollers 200 and 201 are mounted at each side of the supporting surface 198, as shown in Fig. 7. The blank is 15 engaged from above by a pair of rollers 202 and 203 which are mounted on a shaft 204 which is driven from the shaft 178 by a bevel gear connection 205, 206. The blank is fed by the coaction of the two sets of feed rolls along the two sides 20 of the support 198 to a second set of feed rolls shown in Fig. 8. The lower rolls are designated 207 and the upper rolls 208. These rolls are mounted on a shaft 209 which is driven from the shaft 178 by a bevel gear connection 210. The 25 shaft 209 also carries a pair of bending plates 211, 212 which are shown particularly in Figs. 3, 8, and 27. These plates are flared, as shown at 213, and when they are rotated they bend the flaps C and D of the blank B, shown in Fig. 16 30 downwardly, as illustrated in Fig. 8. From the feed rolls 208 the blank is fed to a third set of feed rolls shown in Fig. 9 and designated 215 and 216. As shown in Fig. 1 the support for the blank is now narrowed to the width of the central portion E of the blank or, in other words, to the width of the carton or box. As the blank is being fed by the feed rolls 215, 216 shown in Fig. 9, a second set of bending plates 217, 218 acts on the blank and bends the blank on the lines X and Y, 40 thus bending downwardly the sections F and G. From the showing in Figs. 9 and 27 it will be seen that a pair of folding strips 220 and 221 are supported below the rectangular support 199. These strips are so formed as to engage the flap 45 D and the flap C and to fold them inwardly to position the flap D over the flap C. In this manner the box will be closed to form an open ended rectangular tubular member.

After the flaps C and D have been folded inwardly in the manner just described these flaps will be secured together by pressure exerted by a pair of presser members 225 and 226 which are carried by levers 227 mounted on pivots 228. The upper lever 227 viewing Figs. 13 and 14 has connected thereto a link 229 which is pivoted at 230 to the upper end of a lever 231, this lever being pivoted at 232 to the lever 227. The lever 231 is actuated by a connecting rod or pitman 233 which is connected to an eccentric pin 234 mounted on 60 a disk 235 carried by a shaft 236. The shaft 236 is driven by a gear connection 237, 238 from the drive shaft D.

The lever 231 and link 229 act as a toggle to move the presser members 225 and 226 toward 65 and away from each other or from the open position shown in Fig. 14 to the closed position shown in Fig. 13. These members are carried by blocks 240 which are mounted on the levers 227 and are spring actuated in one direction by means of 70 springs 241, the movement of the members being controlled by stop lugs or set screws 242. By adjusting the screws 242 the distance between the members 225 and 226 can be regulated and the pressure exerted thereby can be controlled. 75

Mechanism for feeding open carton and for placing wrapped article therein

After the carton blank has been folded into a tube means is provided for continuing the forward feeding movement of the blank, this means being particularly illustrated in Figs. 3, 18 to 22 and 27. The blanks are fed by a reciprocating arm 250 which is pivoted at its rear end, to a lever 251 mounted on a fixed pivot 252 and driven by a connecting rod 253 which is actuated by an eccentric pin 254 carried by a disk 255 mounted on a shaft 256. The shaft 256 is driven by a bevel gear connection 257, 258 from the main drive shaft D. As the open ended box is fed along the support 199 the front upper flap K' is raised by means of a lug 260 which, as shown in Fig. 18, is positioned in the path of this flap and, as shown in Figs. 18, 19, 20, and 21, bends the flap K' upwardly and backwardly until the lever or arm 250 has moved over the flap, as shown in Fig. 21. The lug 260 is carried by an arm 261 which carries a roller 262 actuated by a cam 263 mounted on the shaft D.

The arm 250 is provided at its forward end with a pair of transversely extending lugs 265 and 266 and as the arm moves rearwardly viewing Figs. 18 to 21 the tab K' will be pressed downwardly to the position shown in Fig. 21. Then as the arm 250 starting from the position shown in Fig. 22 moves forwardly the tab will move upwardly between the lugs 265 and 266 and the engagement of the lug 266 in the bend of the tab or in the bend at the junction of the tab with the portion E of the blank will cause the open ended box to be fed forwardly or to the left viewing Figs. 18 to 22 inclusive.

The supporting member 199 for the open ended carton extends approximately to the line M in Fig. 3 and thereafter the support is U-shaped in section, as shown in Fig. 30, or in other words, is open at one side. The open side of the support is disposed opposite the discharge end of the pocket P² when the pocket is positioned as shown in Fig. 26 and the wrapped cake is discharged into the U-shaped support by the actuation of the plungers 101 of the pocket P². In Fig. 26 the wrapped cake is illustrated as entering the U-shaped support from the pocket P².

As the open ended carton is fed along the support it will enclose the cake which has been deposited therein and thereupon the feeding movement of the open ended carton and the feeding movement of the cake in the support are synchronized so that the carton and wrapped cake will be fed together. The cake is fed in the U-shaped support by means of a plunger which is reciprocated in the support and is illustrated particularly in Figs. 6, 11, and 12. As shown in Fig. 6 the plunger 270 is connected by a link 271 to an arm 272 of a bell crank lever pivoted to 273. The other arm 274 of the bell crank lever is provided with a roller 275 which is positioned in a cam 276 mounted on a shaft 277. The shaft 277 is driven by a bevel gear connection to the drive shaft D.

The front end of the plunger 270 is shown in Fig. 11 wherein it will be seen that this end carries a head 280 which engages the wrapped cake.

In order to prevent the forward flap R' on the open side of the support from getting in the way of the wrapped cake as the cake enters the carton a lug 281 is formed on an arm 282 pivoted at 283 to the support. The arm 282 is provided 75 with a wedge-shaped lug 284 which is adapted to

engage a wedge 285 carried by a lug 286 which is pivoted at 287 to the plunger. When the plunger 270 moves rearwardly the lug 281 will be raised, thus bending the flap R' outwardly, as shown in Fig. 11. When the plunger 270 moves forwardly to feed the cake the pivoted lug 286 will be swung in an anticlockwise direction viewing Fig. 12 to permit the lug 284 carried by the arm 282 to pass relative to the plunger. However, after the plunger has fed the cake and then moves rearwardly the arm 282 will be swung outwardly to bend the flap R' in the manner just described.

When the carton is moved over the cake and the cake is disposed therein the carton and cake will be fed onto a shelf 290 carried by a vertically mounted slide bar 291 which is slidably mounted in a guide 292. The lower end of the slide bar 291 has connected thereto one arm 294 of a bell crank lever pivoted at 295 and having its other arm 296 connected to one end of a pitman 297 having a roller 298 actuated by a cam 299 mounted on a shaft D (see Fig. 2).

After the carton and article contained therein have been deposited on the shelf the shelf will be raised by the lever mechanism just described into a position in alignment with a supporting table 300. The carton will be fed on the table by means of a vertically mounted bar 301 which depends from a slidably mounted rod 302 which is slidable in a frame 303. The bar 301 has laterally extending tabs 304 and 305 at the ends thereof which engage the rear set of end tabs N and N' of the carton and fold these tabs inwardly. The other end tabs R and R' are engaged by flared ends 306 and 307 on the receiving ends of walls 308 and 309 between which the carton is fed. As the carton is fed onto the supporting table 300 the tabs R and R' will be folded inwardly.

The bar 301 and rod 302 are actuated by a link 310 which is connected at 311 to a pin carried by a disk 312 driven by a sprocket and chain connection 313 from the shaft D. It will be obvious that as the cartons are successively discharged from the shelf 290 to the support 300 by the reciprocation of the bar 301 each carton will feed the cartons in front of it through the carton closing mechanism which will now be described.

As the carton enters between the walls 308 and 309 the tabs N, N' and R, R' have been folded inwardly and the only folding operations now remaining are those necessary to fold the end flaps K and K' and the extensions K² and K³ inwardly to close the box or carton. This is accomplished in the manner illustrated in Figs. 35 to 39 inclusive. When the carton enters the folding mechanism the end flaps K and K' with their extensions are positioned in alignment at the top of the box, as shown in the plan view in Fig. 35. The top of the guideway through which the cartons are fed is formed by a pair of plates 315 having flared receiving ends 316 and having depending flanges 318 and 319 connected to the outer edges thereof by members 320 and 321. The extensions K² and K³ of the end flaps K and K' are folded inwardly in the manner shown in Fig. 36 by the flanges 318 and 319 and as the cartons are fed through the guideway the end flaps K and K' are engaged successively by a plurality of inclined rollers 325, 326, 327, 328, and 329. The rollers are gradually inclined downwardly from a slight angle to the horizontal of the rollers 325 to a steep angle of the rollers 329. The successively acting rollers gradually fold the end flaps K and K' downwardly to the position shown in Fig. 38. In order to insure the entrance of the exten- 75

sions K^2 and K^3 into the carton between the side edges of the tabs N , N' and R , R' and the top and bottom of the carton, guiding members in the form of inclined strips 330 and 331 are provided on the upper surfaces of the support 300 and are positioned to be engaged by the extensions K^2 and K^3 as the end flaps K and K' are fed downwardly. This is clearly illustrated in Figs. 36 to 38 inclusive and in Fig. 38 it will be noted that the extensions K^2 and K^3 have entered the carton.

In order to complete the closure of the box or carton around the wrapped article presser members 335 and 336 are mounted in advance of the rolls 329 adjacent the path of movement of the ends of the carton. The members 335 and 336 are mounted on fixed pivots 337 and are provided at their upper ends with rollers 338 and 339 which are disposed in cam grooves or channels 340 and 341 carried by a frame member 342 . The member 342 has connected thereto an arm 343 which in turn is secured to the rod or slide bar 302 . Thus, as the cam channels or grooves 340 and 341 are reciprocated the presser members 335 and 336 will be swung about their pivots 337 and will press the end flaps K and K' of the carton into closed position, as shown in Fig. 39. The presser members 335 and 336 are normally spread apart or forced away from each other by a spring 345 . The action of the cam grooves or channels 340 and 341 overcomes the tendency of the presser members to move away from each other and forces them into engagement with the end flaps of the box.

From the support or table 300 the cartons are fed to a conveyor belt 350 and are conducted away from the machine.

Operation

The cakes are fed into the machine by the feed chain 65 and when the pocket having a cake reaches a position above the plunger 90 this plunger will be actuated to raise the cake to a position between the reciprocating members or plungers 100 and 101 . When the cake reaches this position a wrapper has been fed by the rotating member 50 and feed rolls 54 and 55 and the wrapper and cake will be fed in the manner shown in Fig. 26 into the pocket P' . This feeding movement is accomplished by the forward movement of the slide bar 102 and rack 103 . After the cake and wrapper have been fed into the pocket P' the pockets P' and P^2 will be rotated by the movement of the vertical slide 164 and the rack and pinion drive shown in Fig. 28 to the position shown in Fig. 30 in which the open ends of the pockets are disposed adjacent each other. When this has been accomplished the lever 126 will actuate the plungers 101 of the pocket P' to feed the wrapper and cake into the upper pocket P^2 . The pockets will then be rotated back through 90° but in opposite directions to the position shown in Fig. 26. The lever 153 will then feed the wrapper and cake from the pocket P^2 into the open side of the guideway over which the cartons are being fed. While the cake is in the pocket P^2 the ends of the wrapper will be crimped by the crimping or folding members 135 and 136 , these members being held open when the cake is fed into the pocket, but being closed to crimp the ends of the wrapper after the cake has entered the pocket.

The carton blanks are fed from the hopper J by the feed rolls 186 and 187 through the chute or guideway 196 to the support 198 . As the blanks move along the support they are folded success-

sively by the rotating cams 211 and 212 , and 217 to fold the carton into an open ended tube. The ends C and D are folded by the curved strips 220 and 221 . The square tube is closed by means of the action of the oppositely moving members 225 and 226 in the manner shown in Fig. 13.

The closed carton is fed along the rectangular support by means of the reciprocating arm 250 , the flap K being raised by the lug 260 and being positioned between the lugs 265 and 266 on the front end of the arm 250 . The carton is thus fed by the forward movement of the arm 250 over the wrapped cake which has been positioned in the support by the actuation of the plungers 101 in the upper pocket P^2 . The cake is fed through the rectangular support with the carton by means of the plunger 270 and the carton with the cake enclosed or disposed therein is fed onto the shelf 290 . The shelf is then raised and the carton and wrapped cake are discharged from the shelf by the movement of the bar 301 , the end tabs N and N' being folded in by the tabs 304 and 305 on the ends of the bar and the other tabs R and R' being folded in by the engagement thereby of the receiving ends 306 and 307 of the side walls 308 and 309 . The end flaps K and K' of the carton are then gradually folded downwardly by the successive action of the rollers 325 to 329 inclusive and the extensions K^2 and K^3 are folded inwardly by the flanges 318 and 319 . These extensions are guided into the openings in the ends of the carton by means of the cam strips 330 and 331 . After they have entered the ends of the cartons the ends are closed by means of the presser members 335 and 336 . From the support 300 the closed cartons are fed to the conveyor 350 by which they are conducted away from the machine.

From the foregoing description it will be seen that the machine described operates automatically to feed and wrap the articles or cakes, fold the cartons, enclose the wrapped articles therein and close the cartons.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. A machine for wrapping and boxing articles comprising means for feeding the articles, means for feeding wrappers into the path of movement of the articles, means for folding the wrappers around the articles, means for feeding carton blanks, means for folding the blanks, means for feeding the folded blanks over the wrapped articles, and means for closing the folded cartons around the wrapped articles.

2. A machine for wrapping and boxing articles comprising means for feeding the articles, means for feeding wrappers into the path of movement of the articles, means for folding the wrappers around the articles, means for feeding carton blanks, means for folding the blanks, a guideway, means for feeding the wrapped articles into the guideway, means for feeding the folded blanks over the guideway, and means for closing the folded cartons around the wrapped articles.

3. A machine for wrapping and boxing articles comprising means for feeding the articles, means for feeding wrappers into the path of movement of the articles, means for folding the wrappers

- around the articles, means for feeding carton blanks, means for folding the blanks, a guideway, means for feeding the wrapped articles into the guideway, means for feeding the folded blanks over the guideway, means for discharging the cartons and wrapped articles therein from the guideway, and means for closing the folded cartons around the wrapped articles.
4. A machine for wrapping and boxing articles comprising means for folding wrappers around the articles, means for folding a blank into an open ended carton, means for feeding the open ended carton over the wrapped article, and means for closing the ends of the carton.
5. A machine for wrapping and boxing articles comprising means for folding wrappers around the articles, means for folding a blank into an open ended carton, a support, means for feeding said open ended carton endwise along the support, means for feeding a wrapped article to and along said support in a position to be surrounded by the carton and in the same direction as the direction of movement of the open ended carton, and means for discharging the carton and article from the support.
6. A machine for wrapping and boxing articles comprising means for folding wrappers around the articles, means for folding a blank into an open ended carton, a support, means for feeding said open ended carton endwise along the support, means for feeding a wrapped article to and along said support in a position to be surrounded by the carton and in the same direction as the direction of movement of the open ended carton, means for discharging the carton and article from the support, and means for closing the ends of the carton.
7. A machine for wrapping and boxing articles comprising means for folding wrappers around the articles, successively acting means for folding a blank into an open ended carton, means for feeding the open ended carton over the wrapped article, and means for closing the ends of the carton.
8. A machine for wrapping and boxing articles comprising means for folding wrappers around the articles, successively acting, rotating means for folding a blank into an open ended carton, means for feeding the open ended carton over the wrapped article, and means for closing the ends of the carton.
9. A machine for wrapping and boxing articles comprising means for folding wrappers around the articles, a support, means for folding a carton blank around the support to form an open ended carton, said support having an opening for receiving a wrapped article, means for feeding the wrapped article into the opening in said support, and means for feeding the open ended carton along said support and over the article and for feeding the article and carton in unison and discharging the carton and article from said support.
10. In a machine of the character described, means for feeding articles to be wrapped, a pocket for receiving the article and wrapper, means for feeding the article and wrapper into said pocket and thereby partially folding the wrapper around the article, a second pocket having means for completing the wrapping of the article, said means including crimping members in said pockets and means to move said members into engagement with the wrapper at the ends of the article when the article and wrapper have been fed into the second pocket, means for feeding the article and wrapper from the first pocket into the second pocket, and means for discharging the wrapped article from the second pocket.
11. In a machine of the character described, a pair of oscillatable pockets mounted on parallel axes disposed one above the other movable through 90° from parallel relation to each other to a position in which they are in alinement with each other, means for oscillating said pockets, each through an angle of 90°, from parallel to alined positions and for oscillating said pockets in reverse directions, each through an angle of 90°, to parallel position, means for feeding an article and wrapper into one pocket and means for discharging a wrapped article from the other pocket when the pockets are in parallel relation, and means for feeding an article and wrapper from one pocket to the other pocket when the pockets are in alinement with each other.
12. In a machine of the character described, a hollow supporting member, means for folding a carton blank around said member into an open ended carton, means for feeding an article into said hollow member in advance of the folded carton, a second support, means engaging the open ended carton along the supporting member and over the article therein, and means engaging the article, for feeding the carton and article from the hollow supporting member to said support.
13. In a machine of the character described, a hollow supporting member, means for feeding a carton blank along said supporting member, means for folding a carton blank around said member, means for feeding an article into said hollow member as the blank is fed, a second support, means engaging the open ended carton for feeding the carton along the supporting member and over the article, and means engaging the article and coacting with the carton feeding means, for feeding the carton and article from the hollow supporting member to said support.
14. In a machine of the character described, a hollow supporting member, means for folding a carton blank around said member, means for feeding an article into said hollow member, a second support, means engaging the open ended carton for feeding the carton along the supporting member and over the article and means engaging the article and coacting with the carton feeding means, for feeding the carton and article from the hollow supporting member to said support, means receiving the carton and article from said last named support, and means for closing the ends of the carton.
15. In a machine of the character described, a support, means for folding a blank around said support and into an open ended carton, means for feeding the open ended carton along the support and over an article to be enclosed therein, means for closing the ends of the carton, said last named means comprising successively acting folding members engageable with the carton ends, and means for feeding the cartons between said folding members.
16. In a machine of the character described, a hollow support, means for feeding an open ended carton along the support, means for feeding an article on the support, said carton feeding means operating to feed the carton over the article, and means carried by the support for bending a flap on the carton away from the path of the carton over the article to prevent the flap from engaging the article as the carton moves thereover.
17. In a machine of the character described,

5 a hollow, U-shaped support, means for feeding an open ended carton along the support, means for feeding an article on the support, said carton feeding means operating to feed the carton over the article, and means carried by the support 10 for bending a flap on the carton at the open side of the supporting member away from the path of the carton over the article to prevent the flap from engaging the article as the carton moves 15 thereover.

18. In a machine of the character described, means for feeding articles to be wrapped, a pocket for receiving the article and wrapper, means for feeding the article and wrapper into said pocket and thereby partially folding the wrapper around 15 the article, a second pocket having means for completing the wrapping of the article, said means including pivoted crimping members carried by the second pocket, means for moving the 20 crimping members to operative positive after an article and wrapper have been fed into the second pocket, means to hold said crimpers out of operative position as the article and wrapper are being fed into the second pocket from the first 25 pocket, means for feeding the article and wrapper from the first pocket into the second pocket, and means for discharging the wrapped article from the second pocket.

19. A machine for wrapping and boxing articles 30 comprising a support, means for feeding an article to said support, means for folding a blank around said support and into an open ended carton along the support, and means for feeding the open ended carton over the article on the support, and 35 means for closing the ends of the carton.

20. A machine for wrapping and boxing articles comprising a support, means for feeding an article to said support, means for folding a blank into an open ended carton, reciprocatable means engageable with a carton flap for feeding the open ended 40 carton over the article on the support, and means for closing the ends of the carton.

21. A machine for wrapping and boxing articles comprising a support, means for feeding an article 45 to said support, means for folding a blank into an open ended carton, means for feeding the open ended carton along said support, means in the path of movement of a carton flap for bending the flap backward as the carton and flap are fed, 50 reciprocatable means engageable with the flap for feeding the carton over the article on the support, and means for closing the carton.

22. A machine for wrapping and boxing articles comprising means for feeding articles to be 55 wrapped, wrapping mechanism comprising a pair of folding pockets disposed one above the other,

means for feeding an article and wrapper into one pocket, means for folding said article and wrapper from said pocket to the other pocket, a hollow support having an open side adjacent the second pocket, means for feeding the wrapped 5 article from the second pocket to the support, means for feeding and folding a carton blank around the support, into an open ended carton, means for feeding the open ended carton along the support and over the wrapped article, and 10 means for closing the ends of the carton.

23. A machine for wrapping and boxing articles comprising means for feeding articles to be wrapped, wrapping mechanism comprising a pair of folding pockets disposed one above the other, 15 means for feeding an article and wrapper into one pocket, means for folding said article and wrapper from said pocket to the other pocket, a hollow support having an open side adjacent the second pocket, means for feeding the wrapped article 20 from the second pocket to the support, means for feeding and folding a carton blank around the support into an open ended carton, means for feeding the open ended carton along the support and over the wrapped article, and successively 25 acting means for folding and tucking in the ends of the carton.

24. A machine for wrapping and boxing articles comprising means for feeding articles to be wrapped, wrapping mechanism comprising a pair 30 of folding pockets disposed one above the other, means for feeding an article and wrapper into one pocket, means for folding said article and wrapper from said pocket to the other pocket, a hollow support having an open side adjacent the second 35 pocket, means for feeding the wrapped article from the second pocket to the support, means for feeding and folding a carton blank around the support, into an open ended carton, means for feeding the open ended carton along the support 40 and over the wrapped article, and means disposed at an angle to the path of movement of the carton over the wrapped article for closing the ends of the carton.

25. A machine for wrapping and boxing articles 45 comprising means for folding wrappers around the articles, means for folding a blank into an open ended carton, a support, means for feeding the open ended carton endwise along the support, means for feeding a wrapped article along 50 the said support in the same direction as the direction of movement of the open ended carton and for placing the wrapped article in the open ended carton, and means for closing the ends of said carton. 55

JOHN VAN BUREN.
